CLAIM

The ornamental design for a rechargeable vacuum cleaner, as shown.

DESCRIPTION

FIG. 1 is a top, front and right side perspective view of a rechargeable vacuum cleaner showing our new design;

FIG. 2 is a bottom, rear and right side perspective view thereof;

FIG. 3 is a right side elevational view thereof, the opposite side being a mirror image; and

FIG. 4 is a top, front and left side perspective view thereof.

*Fig. 1**Fig. 2**Fig. 3*

Fig. 4
